UNITED STATES PATENT OFFICE.

ERNEST S. JOHNSON, OF WEBSTER CITY, IOWA.

DESIGN FOR A HEAT-INSULATED CONTAINER.

54,631.

Specification for Design.

Patented Mar. 9, 1920.

Application filed April 28, 1919. Serial No. 293,357. Term of patent 14 years.

To all whom it may concern:

Be it known that I, ERNEST S. JOHNSON, a citizen of the United States of America, and a resident of Webster City, Hamilton county, Iowa, have invented a new, original, and ornamental Design for Heat-Insulated Containers, of which the following is a specification, reference being had to the accompanying drawing, forming part thereof.

The figure is an elevation of a heat-insulated container, showing my new design.

I claim:

The ornamental design for a heat-insulated container, as shown.

Signed at Waterloo, Iowa, this 12th day of April, 1919.

ERNEST S. JOHNSON.
